UNITED STATES PATENT OFFICE.

CHARLES H. JULL, OF BEN AVON, PENNSYLVANIA, ASSIGNOR TO PITTSBURGH-ERIE
SAW COMPANY, OF PITTSBURGH, PENNSYLVANIA, A CORPORATION OF PENNSYLVANIA.

POWER SAW.

Application filed October 30, 1924. Serial No. 746,909.

To all whom it may concern:

Be it known that I, CHARLES H. JULL, a citizen of the United States, and resident of Ben Avon, in the county of Allegheny and State of Pennsylvania, have invented certain new and useful Improvements in Power Saws, of which the following is a specification.

This invention relates to saws, and, while not limited thereto, relates more particularly to power meat saws for use by butchers and has for its object a saw of this character adapted to be mounted on a butcher's block, table or other meat support and to have a universal movement relative thereto.

Another object is to provide a saw of this character which is devoid of all flexible shafts or other flexible power conducting means, and receives its power directly through gearing from a motor carried by the saw frame.

A still further object is to provide a saw of this class having the novel construction, combination and design of parts hereinafter described in detail and illustrated in the accompanying drawings.

In the drawings, Figure 1 is a side elevation showing a saw, constructed in accordance with this invention, mounted on a butcher's block.

Figure 2 is a top plan view thereof.

Figure 3 is an enlarged side elevation thereof showing the details of the saw mounting.

Figure 4 is a rear elevation of the saw mounting.

Figure 5 is a sectional plan on the line V—V of Figure 3.

Figures 6 and 7 are transverse sectional elevations on the lines VI—VI and VII—VII, respectively, of Figure 3.

Referring more particularly to the drawings, the letter A designates the butcher's block or table, which may be of any well known and usual design generally used for supporting meat during the cutting operations.

A pair of brackets 2 and 3 are secured to the rear face of the block A and support a pair of rail or track rods 4 and 5 adapted to carry the saw. A wheeled carrier comprising a body portion 6 and supporting wheels 7 is mounted for longitudinal movement on the track members 4 and 5.

55 A supporting member comprising a head

portion 8 and a shank portion 9 is pivotally mounted on the carrier body 6 by having its shank portion 9 fitted within a vertical recess in the body 6 so as to provide for a horizontal swinging movement of said supporting member. A circular housing member 10 having a bracket portion 11 projecting forwardly from its bottom, has its bracket portion pivotally secured to the head 8 of said supporting member, as at 12, so as to be movable about a horizontal axis.

An elongated substantially U-shaped saw frame B comprising a top bar 14 and end portions 15 and 16 and circular mounting disk 17 is preferably formed in one piece by casting. The mounting disk 17 is adapted to be mounted in the circular housing member 10 so as to support the saw frame B and permit said frame to be turned about its horizontal axis to various angular positions.

A friction piece 20 is mounted in a recess in the housing 10 and is adapted to be forced down into engagement with the mounting disk 17 by a screw 21 to lock the saw frame in its adjusted angular positions.

A shaft 23 is journaled in a bearing 24 in the rear end portion 15 of the frame B and a head band wheel or pulley 25 on the inner end thereof and a beveled gear 26 on its outer end. The wheel or pulley 25 is the power wheel or pulley for operating the saw blade 27 and receives its power from a motor 28 supported on a bracket 29 mounted on the rear face of the disk 17 of the saw frame. The motor 28 has its armature shaft 30 provided with a pinion gear 31 which is in mesh with the beveled gear 26.

An idler band wheel or pulley 32 is mounted for free rotation on a shaft 33 mounted in a longitudinally adjustable bearing 34 mounted in a suitable slot 35 in the forward end portion 16 of the saw frame B. The bearing 34 is adapted to be adjusted by a threaded adjusting rod 35a threaded in a nut 36 fixed to the portion 16 of the saw frame.

The continuous band saw blade 27 is trained around the wheels or pulleys 25 and 32 and is passed through blade turning devices 37 and 38 secured to each of the end portions 15 and 16 so that the cutting portion of the blade 27 between the end pieces 15 and 16 is turned in a vertical position.

A meat supporting plate 39 is mounted on the forward face of the rear end portion 110

15 of the saw frame. The plate 39 is secured in position by stud screws 40 passing through vertically arranged slots 41 in the plate and screwed into a bracket 42 on the portion 15 of the saw frame, so as to provide a limited vertical movement of the plate when the saw frame is moved or tilted upwardly. The plate 39 is also provided with a vertically arranged slot 44, through 10 which the saw blade 27 passes.

The saw frame B has a handle member 45 on its forward end, which preferably has a control switch for the motor mounted therein and operated by the trigger 46. The control switch is not shown, since it may be of any standard construction and forms no part of this invention.

In operation, the saw frame is movable 20 bodily along the track rails or rods 4 and 5 by means of the wheeled carrier and, therefore, may be moved to different positions along the article being sawed. The pivotal connection between the shank 9 of the supporting member and the carrier permits the saw frame to be swung to various 25 horizontal angular positions, and the pivotal connection at 12 between the head 8 of the supporting member and housing 10 permits the saw frame to be swung vertically to various angular positions, thus permitting a limited universal movement of the 30 saw frame. In addition to the universal movement of the saw frame, the frame may be turned about its longitudinal axis to various angular positions, due to the mounting 35 of the disk 17 in the housing 10.

Normally the saw frame is held in raised 40 position. That is, the housing 10 and saw frame B are rocked about the pivotal connection 12 so as to elevate the saw frame above the top of the block or table A, as shown in dotted lines in Figure 1. The motor 28 is normally of sufficient weight to raise the saw frame into this normal position. However, it will be understood that if desired suitable counterweights may be 45 employed if the weight of the motor is insufficient.

While I have shown and described only 50 one specific embodiment of my invention, it will be understood that I do not wish to be limited thereto since various modifications may be made without departing from the scope of my invention as defined in the appended claims.

I claim—

1. A power meat saw comprising in combination a track, a wheeled carrier mounted on said track and adapted to move longitudinally thereof, a supporting member pivotally mounted on said carrier for horizontal swinging movement, a housing pivotally mounted on said supporting member for vertical swinging movement, and a saw support revolvably mounted in said housing and

adapted to be turned to various angular positions, said saw support comprising an elongated frame member having a mounting disk on its rear end and mounted in said housing, a pair of band wheels journaled 70 adjacent the opposite ends of said frame, a band saw trained around said band wheels, a motor secured to the rear face of said mounting disk, and suitable drive connections between said motor and at least one 75 of said band wheels.

2. The combination with a butcher's block, table, bench or the like, of a track rigidly secured along one side thereof, a wheeled carrier mounted on said track and adapted 80 to move longitudinally thereof, a supporting member pivotally mounted on said carrier for horizontal swinging movement, a housing pivotally mounted on said supporting member for vertical swinging movement, and a saw support revolvably mounted in said housing and adapted to be turned to various angular positions, said saw support comprising an elongated frame member having a mounting disk on its rear end and 85 mounted in said housing, a pair of band wheels journaled adjacent the opposite ends of said frame, a band saw trained around said band wheels, a motor secured to the rear face of said mounting disk, and suitable 90 drive connections between said motor and at least one of said band wheels.

3. A power meat saw comprising in combination a fixed track, a carrier mounted on said track and adapted to move longitudinally thereof, a supporting member pivotally mounted on said carrier for horizontal swinging movement, a housing pivotally mounted on said supporting member for vertical swinging movement, and a saw support revolvably mounted in said housing and adapted to be revolved about its longitudinal axis to various angular positions, said saw support comprising an elongated frame member having a mounting disk on 110 its rear end and mounted in said housing, a saw blade mounted in said frame, a motor secured to the rear face of said mounting disk, and suitable operating connections between said motor and said saw blade. 115

4. A power meat saw comprising in combination a fixed track, a carrier mounted on said track and adapted to move longitudinally thereof, a supporting member pivotally mounted on said carrier for horizontal swinging movement, a housing pivotally mounted on said supporting member for vertical swinging movement, and a saw support revolvably mounted in said housing and adapted to be turned to various angular 125 positions, said saw support comprising an elongated frame member having a mounting disk on its rear end and mounted in said housing, a saw blade mounted in said frame, a motor secured to the rear face of said 130

mounting disk, and suitable operating connection between said motor and said saw blade.

5. The combination with a butcher's block table, bench or the like, of a track rigidly secured along one side thereof, a carrier mounted on said track and adapted to move longitudinally thereof, a supporting member pivotally mounted on said carrier for 10 horizontal swinging movement, a housing pivotally mounted on said supporting member for vertical swinging movement, and a saw support revolvably mounted in said housing and adapted to be revolved about its longitudinal axis to various angular positions, said saw support comprising an elongated frame member having a mounting disk on its rear end and mounted in said housing, a saw blade mounted in said frame, 15 a motor secured to the rear face of said mounting disk, and suitable drive connections between said saw blade and said motor.

6. A power meat saw comprising in combination, a carrier member, a supporting member pivotally mounted directly on said carrier for horizontal swinging movement, a housing pivotally mounted directly on said supporting member for vertical swinging movement, and a saw support revolvably mounted in said housing and adapted to be revolved about its longitudinal axis to various angular positions, said saw support comprising an elongated frame member having a mounting disk on its rear end and mounted in said housing, and a saw blade operatively mounted in said frame.

7. A power meat saw comprising in combination, a carrier member, a supporting member pivotally mounted directly on said carrier for horizontal swinging movement, a housing pivotally mounted directly on said supporting member for vertical swinging movement, and a saw support revolvably mounted in said housing and adapted to be revolved about its longitudinal axis to

various angular positions, said saw support comprising an elongated frame member having a mounting disk on its rear end and mounted in said housing, a saw blade operatively mounted in said frame, power 50 means secured to the rear face of said mounting disk, and suitable operating connections between said power means and said saw blade.

8. The combination with a meat support, 55 of a track secured along one side thereof, a carrier mounted on said track and adapted to move longitudinally thereof, a supporting member pivotally mounted directly on said carrier for horizontal swinging movement, a housing pivotally mounted directly on said supporting member for vertical swinging movement, and a saw support revolvably mounted in said housing and adapted to be revolved about its longitudinal axis 60 to various angular positions, said saw support comprising an elongated frame member having a mounting disk on its rear end and mounted in said housing, and a saw blade operatively mounted in said frame.

9. The combination with a meat support, 70 of a track secured along one side thereof, a carrier mounted on said track and adapted to move longitudinally thereof, a supporting member pivotally mounted directly on 75 said carrier for horizontal swinging movement, a housing pivotally mounted directly on said supporting member for vertical swinging movement, and a saw support revolvably mounted in said housing and adapted to be revolved about its longitudinal axis 80 to various angular positions, said saw support comprising an elongated frame member having a mounting disk on its rear end and mounted in said housing, a saw blade operatively mounted in said frame, and power 85 means for operating said saw blade.

In testimony whereof I have hereunto signed my name.

CHARLES H. JULL.
